UNITED STATES PATENT OFFICE.

HAROLD C. FREEMAN, OF RACINE, WISCONSIN, ASSIGNOR TO THE S. FREEMAN & SONS MFG. CO., OF RACINE, WISCONSIN.

CIRCULATING DEVICE FOR INTERNAL-COMBUSTION BOILERS.

1,262,035.

Specification of Letters Patent.

Patented Apr. 9, 1918.

Application filed May 22, 1916. Serial No. 99,184.

To all whom it may concern:

Be it known that I, HAROLD C. FREEMAN, a citizen of the United States, and resident of Racine, in the county of Racine and State 5 of Wisconsin, have invented certain new and useful Improvements in Circulating Devices for Internal-Combustion Boilers; and I do hereby declare that the following is a full, clear, and exact description thereof.

10 The present invention relates to new and useful improvements in boilers of the internal furnace type.

A common disadvantage of the internal furnace type of boilers is that an unequal 15 heating is exerted on the water in the boiler whereby the lower portion of the boiler below the ash pits of the furnace tubes does not receive a sufficient supply of heat, and this condition interferes materially with the 20 efficient operation of the boiler.

It is therefore the object of the present 25 invention to overcome this disadvantage and it is more specifically an object in this connection to provide a circulating system for the water within the boiler, whereby a positive flow of water is set up within the boiler to remove the aforementioned objectionable feature.

It is further an object to provide such a 30 circulating system wherein a portion of the flow passes directly through the combustion chamber and thus receives an exceedingly great amount of heat to provide for a maximum positive flow of water.

35 It is still further an object of the invention to provide such a circulating system in connection with internal furnace boilers which may be associated therewith in a manner necessitating no change in the otherwise efficient general construction of this 40 type of boiler.

With the above and other objects and advantages in view, the invention resides more particularly in the novel combination, arrangement and formation of parts more particularly hereinafter described and pointed out in the appended claim.

In the drawings:

Figure 1 is a top plan view of an internal 50 furnace boiler of a double furnace type with the improved circulating means associated therewith.

Fig. 2 is a transverse sectional view therethrough on the line 2—2 of Fig. 1.

Fig. 3 is a similar view on the line 3—3 of Fig. 1.

Referring now more particularly to the accompanying drawings, 5 designates the usual cylindrical body of the boiler in the lower portion of which are disposed the furnace tubes 6 which are open at the front of the boiler and which communicate at the rear of the boiler with the gas combustion chamber 7 from the upper portion of which the usual gas flues 8 extend longitudinally 60 through the boiler above the furnace tubes and communicate with the usual breeching 8^a. Thus while the upper portion of the boiler receives heat from the furnace tubes 6 and the flues 8, the lower part of the boiler 70 does not receive corresponding sufficient heat and thus this improper heating results in an improper circulation of water with its consequent well known disadvantages.

The improved circulating means to overcome this disadvantage comprises a water tube 9 which extends diagonally in the combustion chamber and has its ends disposed outwardly thereof and provided with connecting boxes 10, to the upper of which is 75 connected a pipe 11 that extends forwardly along the upper portion of the boiler and communicates therewith at 12.

To the lower connecting box 10 is connected a pipe 13 which extends to the rear 85 of the boiler and is then directed laterally at 14 along the back of the boiler and then directed at 15 through the lower part of the combustion chamber and extended into the boiler and terminates at 16 adjacent the 90 front portion of the boiler, that portion of the pipe which passes through the combustion chamber being protected as by an enlarged portion 17 of the fire lining of the chamber. The inlet port at 16 of this circulating system is thus disposed forwardly of the outlet port 12 and which latter port is near the rear of the boiler, and thus the relatively cold water in the lower portion 95 of the boiler flows through the pipe portions 15, 14 and 13 and through the diagonal water tube 9 in the combustion chamber where it is subject to a great degree of heat to thus render more positive the circu- 100

lation, and finally through the pipe 11 back into the boiler.

The essential feature of the present invention is the provision of a water tube in the combustion chamber which communicates at its upper end with the top of the boiler and at its lower end with the bottom of the boiler at their intermediate portions, and the embodiment of the invention illustrated is the one most particularly adapted for the certain specific form of boiler with which it is shown associated and it will be understood that various embodiments of the invention may be employed to meet varying conditions and to adapt the device for various specific types of boilers, and either or both of the pipes 15 and 11 may be disposed within the boiler or may be disposed entirely outwardly of the boiler should conditions render this arrangement advisable.

I claim:

A circulating device for an internal combustion furnace boiler including a boiler shell, a furnace shell therein, and a combustion chamber at the rear of the furnace shell, of a straight water tube extending dia-

nally across the combustion chamber with its ends projected exteriorly thereof, boxes carried by the ends of said tube, a pipe connected with the box on the uppermost end of said tube, said pipe extending forwardly along the upper portion of the boiler and communicating therewith, a second pipe connected with the box carried by the lowermost end of said tube and extending to the rear of the boiler and then directed laterally along the back of the boiler and through the lower part of the combustion chamber and extended into the boiler and communicating therewith adjacent the front portion thereof, and an enlargement formed by the firing lining of the combustion chamber for protecting the portion of the pipe passing therethrough substantially as described.

In testimony that I claim the foregoing I have hereunto set my hand at Racine, in the county of Racine and State of Wisconsin, in the presence of two witnesses.

HAROLD C. FREEMAN.
